(57) **CLAIM**

We claim the ornamental design for the frontal geometry of a syringe, as shown and described.

DESCRIPTION

FIG. 1 is a front perspective view showing our new design. FIG. 2 is a rear perspective view thereof.

FIG. 3 is a side elevation view thereof.

FIG. 4 is a side elevation view thereof; and,

FIG. 5 is a front elevation view thereof.

The broken line showing of syringe is included for the purpose of illustrating portions of the design and forms no part of the claimed design.
